UNITED STATES PATENT OFFICE.

SAMUEL A. GOULD, OF CHICAGO, ILLINOIS.

HINGE FOR CAKE-GRIDDLES, &c.

SPECIFICATION forming part of Letters Patent No. 340,208, dated April 20, 1886.

Application filed September 3, 1883. Renewed December 31, 1885. Serial No. 187,317. (No model.)

To all whom it may concern:

Be it known that I, SAMUEL A. GOULD, of Chicago, county of Cook, and State of Illinois, have invented certain new and useful Improvements in Hinges for Cake-Griddles, &c., of which the following is a specification.

My invention is for improvements in hinges as applied to "cake-griddles," (as shown in the accompanying drawings,) and all other similar articles composed of two or more parts united by hinge-joints, where said parts are required to be in a supported level position when open. Its advantages over the old hinge joint ordinarily used in such cases are, it is much more substantial, furnishing a regular level of the hinged parts, its construction is simple and economical, no drilling being required, the parts being united as cast or made, and fastened in position by the pin or wire or any other suitable device, which acts both as a lock of the hinge and fixed support to hold the parts in a line position.

The mechanism and construction of said invention are as follows, reference being had to the accompanying drawings.

Figure 1 shows a plan view of a cake-griddle with the said hinge applied; Fig. 2, a sectional view of the same through the line *x x*;

Fig. 3, the locking pin before using, and Fig. 4 the same after it is fixed into position in the hinge by clinching the end.

Said hinge is composed of three parts—first, the T-shaped projection A, with a slot or groove, D, around the center of the head of the T-bar A; second, a corresponding projected ear, and a notch or groove corresponding to said groove D in the T-bar; and, third, the wire or pin, as shown by Figs. 3 and 4. The said T-projection A being placed in the corresponding part, B, the wire or pin C, as it appears in Fig. 3, is inserted in the groove D and fastened by clinching or turning down the end, as shown in Fig. 4.

What I claim is—

A hinge with a T-shaped projection, having a groove in the center of the same, a projection provided with two or more perforated ears, and a notch or groove corresponding to the groove in the T-projection, and the wire or pin forming the lock or fastening, substantially as described and shown.

SAMUEL A. GOULD.
